US00D717619S

(12) **United States Design Patent**
Kundracik et al.

(10) **Patent No.:** US D717,619 S
(45) **Date of Patent:** ** Nov. 18, 2014

(54) **TOOL HANDLE**

(71) Applicant: **Ridge Tool Company**, Elyria, OH (US)

(72) Inventors: **Richard M. Kundracik**, Elyria, OH (US); **Jason J. Boggs**, South Amherst, OH (US); **Glen R. Chartier**, Avon Lake, OH (US); **Prasad Patil**, Pune (IN); **Rahul Maruti Nanche**, Maharashtra (IN); **Sandeep Sidagouda Patil**, Pune (IN)

(73) Assignee: **Ridge Tool Company**, Elyria, OH (US)

(**) Term: **14 Years**

(21) Appl. No.: **29/486,339**

(22) Filed: **Mar. 28, 2014**

Related U.S. Application Data

(63) Continuation-in-part of application No. 14/202,611, filed on Mar. 10, 2014, which is a continuation-in-part of application No. 13/908,316, filed on Jun. 3, 2013.

(30) **Foreign Application Priority Data**

Apr. 1, 2013 (IN) 1263/MUM/2013
